UNITED STATES PATENT OFFICE.

CLIO B. YAW, OF NEW YORK, N. Y., ASSIGNOR TO WYCKOFF, SEAMANS & BENEDICT, OF ILION, NEW YORK, A CORPORATION OF NEW YORK.

TYPE-WRITING MACHINE.

1,036,947.

Specification of Letters Patent. Patented Aug. 27, 1912.

Application filed March 30, 1908. Serial No. 308,878.

To all whom it may concern:

Be it known that I, Cléo B. Yaw, citizen of the United States, and resident of the borough of Brooklyn, city of New York, in the county of Kings and State of New York, have invented certain new and useful Improvements in Type-Writing Machines, of which the following is a specification.

My invention relates to typewriting machines and has for one of its objects the provision of improved devices for writing tags, labels or the like.

Another object is to provide means for feeding the work sheet or paper, whereby said work sheet as it is fed through the machine is positively connected with the platen so that it cannot be displaced relatively to said platen.

Another object is to provide improved means for guiding the work sheet or paper as it is fed through the machine.

Another object is to provide means for line spacing a divided or sectional platen whereby a plurality of platen sections may be line spaced at a single actuation of said device, at one time, said line spacing device being also adapted to actuate one of said platen sections intermittently so that the latter section is at times line spaced and at other times is not line spaced when said actuating device is operated.

Another object is to provide a divided or sectional platen of improved construction.

Another object is to provide a copy holder which is adapted to be automatically actuated at intervals during the operation of the machine.

To the above and other ends my invention consists of the features of construction, combinations of devices and arrangements of parts hereinafter fully described and particularly pointed out in the claims.

In the accompanying drawings illustrating one form of my invention, Figure 1 is a side elevation of the upper part of a typewriting machine embodying my invention, parts being omitted and broken away. Fig. 2 is a fragmentary top plan view of the machine, parts being omitted. Fig. 3 is a full-sized side elevation of the upper part of the machine showing the platen carriage with my invention applied thereto, parts being broken away for the sake of clearness. Fig. 4 is a full-sized top plan view of the right-hand end of the platen carriage, parts

being broken away. Fig. 5 is a full-size transverse sectional view of the platen and platen carriage taken on the plane represented by the line *x* in Fig. 2 and looking in the direction of the arrow. Fig. 6 is a full-size fragmentary longitudinal sectional view of the platen. Fig. 7 is a transverse sectional view of the platen taken on the plane represented by the line *y*, *y* in Fig. 6 and looking in the direction of the arrow. Fig. 8 is a full-sized perspective view of one of the guides for the work sheet or paper. Fig. 9 is a full-sized perspective view of another guide for the work sheet or paper. Figs. 10, 11 and 12 are fragmentary full-sized side elevations of the line spacing devices, said devices being shown in different stages of operation. Fig. 13 is a full-sized perspective view of the line spacing ratchet wheels and the right hand platen head. Fig. 14 is a front elevation of the upper part of the machine, parts being omitted and broken away. Fig. 15 is a face view of one kind or style of work sheet or paper to which my invention is adapted. Fig. 16 is a transverse sectional view of the paper roll holder, the section being taken through the center of the holder.

I have shown my invention as applied to a typewriting machine generally resembling the well known Remington typewriter, but it is to be understood that the nature of the invention is such that it may be readily adapted to other forms of writing machines. I have furthermore shown a form of my invention which is especially adapted for use with a narrow perforated strip or work sheet of the style shown in Fig. 15, said strip being adapted to the preparation of car record tags for a car record apparatus such as that shown and described in the patent to W. E. Beecham, No. 618,388, dated January 31st, 1899. It will be obvious however that the perforated strip of the character shown is only one of many forms of work sheet with which my invention may be employed.

In the drawings the main frame of the machine comprises corner posts 1 which rise from a base (not shown) and which sustain a top plate 2. Arranged above the top plate is a platen frame or carrier composed of side bars 3 and 4, a rear bar 5 and a front bar 6. The front bar 6 has a bearing block 7 suitably secured to it and said

bearing block has journaled on it a wheel or roller 8 which coöperates with a guide rail 9 carried on supports 10 which project above the top plate and are pivoted on the frame of the machine in the usual manner. The guide rail 9 is usually shiftable but in the present instance I prefer to maintain said guide rail in a fixed position and this is accomplished by means of plates 11 (Fig. 2) which are secured to the top plate by screws 12 and each of which contacts at its rear edge with one of the supports 10 where the latter passes through the top plate, so as to prevent rotary motion of said support 10 on its pivot. The rear bar 5 of the platen frame has pins 13 projecting laterally from its ends and said bar is slotted to receive downwardly extending arms 14 which are pivoted on said pins 13 and are connected 15 in the usual manner by a cross rod 15 supported at its end by screw pivots 16 (Fig. 4), said screw pivots being adjustably secured in the forwardly projecting side arms 17 of a carriage truck 18. The usual limiting screws 19 in the sides of the carriage truck are in the present case screwed in until the bars at each side engage the pin 13 projecting from the neighboring end of the rear bar 5 of the platen frame so that said 20 bar instead of being rotatable about the pivots 16 is held from shifting motion and maintained in a fixed relation with the carriage truck. Said truck carries the usual wheels or rollers 20 which coöperate with a 25 guide rail 21 supported on standards 21 rising from the top plate. The platen carrier or frame and the carriage truck comprise, as is well understood, a platen carriage, but in the present instance said platen frame instead of being shiftable on the truck is held in a fixed relation therewith but is capable of being swung upward about the pivots 13 in the usual manner to expose the writing.

45 Journaled in the side bars 3 and 4 of the platen carrier is a platen axle 22 provided at its ends with the usual finger wheels 23. Said axle supports a platen of novel construction and illustrated in detail in Figs. 50 5, 6 and 7. The platen as herein shown is a divided one comprising two parts or sections each rotatable about the same pivotal axis independently of each other. The left hand or longer section of the platen comprises an 55 inner thin metal tube 24 which surrounds the platen axle 22 and which, at its left-hand end, has suitably secured to it, as by soldering, an annular plate or ring 25. Surrounding the inner tube 24 is a somewhat 60 shorter metal tube 26 the left-hand end of which is soldered also to the ring 25 and the right-hand end of which is soldered to a similar but somewhat thicker annular plate or ring 27 which surrounds and is 65 soldered to the inner tube 24. A platen head

28 is secured to the annular plate 25 by screws 29, said platen head being perforated to permit of the passage therethrough of the platen axle 22 and having a central boss or hub 30 which receives a set screw 31, said set screw abutting against the platen axle and maintaining the left-hand platen section in fixed relation with said axle. The outer tube 26 receives a sheath or covering 32 of rubber. Seated within the right-hand end of the inner tube 24 is a metal disk 33 which is suitably secured in place as by soldering. A line spacing wheel 34 is secured to the disk 33 by screws 35 which pass through the line spacing wheel 36 and take into threaded openings in the disk. The line spacing wheel is depressed as indicated at 36 for the sake of lightness and is provided with a hub 37 which receives a set screw 38, the end whereof abuts against the platen axle 22. The line spacing wheel 34 is provided with peripheral ratchet teeth 39, as clearly shown in Fig. 13, said teeth being spaced apart a line space unit in the usual manner. The inner end of the line spacing wheel is reduced as indicated at 37 to permit entrance into the inner tube 24 thereby forming a shoulder 40. Mounted upon the inner tube 24 to the left of the shoulder 40 is a shorter platen section which comprises a metal core or tube 41, said core at its left end surrounding and being rotatable upon the right-hand end of the tube 26, the sheath 32 on said tube 26 being cut off to afford a bearing for the core 41, as clearly shown in Fig. 6. Integral with the right-hand end of the core 41 is an annular plate-like portion or flange 42 which surrounds and bears upon the inner tube 24. Secured to the portion 42 by headed screws 43 is a line spacing wheel 44, said wheel being bored out to fit over and bear upon the inner tube 24. As most clearly appears in Fig. 13 the line spacing wheel 44 is provided with peripheral ratchet teeth. Some of these ratchet teeth indicated by the numeral 45 are sharp-pointed and others indicated by the numeral 46 have broad tops, crowns or faces. The teeth 45 alternate with the teeth 46. The core or tube 41 of the short platen section is provided with a sheath or cover 47. Rivets 48 pass radially through the cover 47 and tube 41 and their outer heads 49 project some distance beyond the sheath 47 and are rounded so as to provide lugs or projections for engaging the work sheet in a manner presently to be described. Six of said projections are shown in the drawings disposed about centrally of the length of the short platen section and spaced equally apart, but the number of said projections, it is to be understood, may be greater or less than six.

It will be seen from an inspection of Fig. 6 that the short platen section is held in

fixed relation lengthwise of the long section, being confined between the shoulder or face 40 of the ratchet wheel 34 and the right-hand end of the sheath or cover 32. It will 5 further be apparent that the short platen section may be given rotary or line space movement independently of and upon the long platen section, and it will also be apparent that the long platen section may be 10 given a rotary or line space movement independently of the short platen section.

Means for communicating line space movements to the two platen sections will now be described.

15 As clearly shown in Figs. 1 and 3 an arm 50 projects downwardly and forwardly from the side arm 4 of the platen frame and pivoted to said arm at 51 is a line space actuating lever 52 of suitable construction, 20 said line space lever having a forwardly and downwardly curving arm or handle 53 and an upwardly projecting arm 54. A coiled restoring spring 55 surrounds the pivot 51 of the line spacing lever and tends to maintain 25 the latter normally in engagement with a pin 56, which pin is removably secured on an arm 57 fixed to and extending forwardly and upwardly from the side bar 4 of the platen frame. As shown in Figs. 2, 4 and 30 14, the limiting pin 56 is provided with an annular flange 58 which is received in a slot 59 formed in the arm 57, said flange 58 being maintained in its slot by a flat spring 60 which is secured to the arm 57 by a headed screw 60^a and bears normally against the flange 58, the construction being such that the pin is held from casual endwise displacement. Pivoted loosely at 61 at the upper end of the arm 54 of the line space actuating lever is a horizontally disposed and rearwardly projecting pawl arm 62, said pawl arm being provided with a pawl tooth 63 which normally rests on one or another of the ratchet teeth on the line spacing 40 ratchet wheel 44, being maintained thereagainst by gravity. Below the pivot 61 the lever arm 54 is provided with a threaded opening which receives a shouldered screw 64, said screw serving as a fulcrum for an 45 angular pawl arm 65. The pawl arm 65 extends upwardly from the fulcrum 64 and thence is bent rearwardly so as to lie substantially parallel with the pawl arm 62, said pawl arm 65 being provided with a 50 pawl tooth 66. The pawl arm 65, as will be clearly seen from Figs. 2 and 4, lies to the right of the pawl arm 62 being disposed at the opposite side of the lever arm 54, so that said pawl arm 65 is in position to coöperate 55 with the teeth of the line space wheel 34. The pawl arm 65 is loosely fulcrumed on the screw 64 and tends to drop by gravity into engagement with the line space wheel 34. An angular pin 67, however, is secured to 60 the top of the pawl arm 65 near its rear or

free end, said pin extending upward from the pawl arm 65 and then being bent horizontally leftward so as to lie over and in the path of the pawl arm 62. In some positions of the line spacing devices the pawl arm 65 engages operatively with the line spacing wheel 34, but in other positions of the parts the pawl arm 65 and the line spacing wheel 34 are held from coöperative engagement by means of the pin 67 coöperating with the pawl arm 62. This operation of the parts will be more clearly understood from a subsequent explanation. An arm 68 extends upwardly from the side bar 4 of the platen frame and has secured to it a horizontally disposed and inwardly projecting pin 69 which serves as a limiting stop for the pawl arm 62. The rear bar 5 of the platen frame is provided near its right-hand end with a flattened or plate-like portion 70, best shown in Figs. 2, 3 and 4. A spring arm 71 is secured to the under side of the part 70 by a headed screw 72, said spring arm extending downwardly and forwardly and being bifurcated at its forward end. 75 The fingers 73 of the bifurcated end are curled back on themselves to hold the axle of a detent wheel 74 which is received between said fingers 73 and is maintained by the inherent spring pressure of the arm 71 in engagement with the teeth 39 of the ratchet wheel 34. A spring arm 75, similar to the arm 71, is secured at the left of the arm 71 to the under side of the portion 70 by a headed screw 76, said arm projecting 80 downwardly and forwardly and being bifurcated to provide fingers 77. The ends of the fingers 77 are curled back on themselves to provide bearings for the axle of a detent roller 78 which is received between the fingers 77, and coöperates with the teeth of the ratchet wheel 44 to hold the latter, and with it the shorter platen section to which it is 85 fixed, in desired position.

Referring now to the paper feeding devices, hanger arms 79 are pivoted at 80 in lugs 81 rising from the rear bar 5 of the platen frame, as clearly shown in Figs. 2 and 5. The hanger arms 79 support at their lower ends a rod 82 upon which is mounted 110 a plurality of feed rollers 83, three of said feed rollers being shown. The feed rollers 83 may be of suitable construction and are adapted to coöperate with the longer or left-hand platen section in a known manner, 115 being maintained in operative engagement with said platen section by flat pressure springs 84 which are fixed to the under side of the arms 79 by screws 85, the upper free ends of said springs 84 coöperating with 120 lugs 86 on the rear bar 5 of the platen frame. Above the arms 79 and forward of their pivots a feed roll release shaft 87 extends from side to side of the platen frame in rear of the platen, said shaft being journaled in 125 130

the side bars 3 and 4. A paper apron 88 is provided at its ends with ears 89 which are curled around and loosely clasp the shaft 87 thereby pivotally connecting the paper apron with said shaft, said paper apron extending downwardly and forwardly and being cut away to permit the feed rollers 83 to protrude therethrough toward the platen.

The paper feeding and guiding devices 10 thus far described are of known construction and it is not thought necessary to discuss them in greater detail. It will be noted from an inspection of Fig. 2 that said paper feeding devices coöperate with 15 the longer platen section only. A combined guide and indicating plate 90 extends from side to side of the longer or left-hand platen section at the front thereof. Said plate 90 is provided with ears or tabs 91 which are 20 perforated to receive headed screws 92 which take in threaded openings in the front bar 6 of the platen frame, thereby securing the plate 90 to said platen frame. The upper portion of the plate 90 terminates in a 25 straight edge 93 which serves as a line indicator in a manner presently to be described. Below the ears 91 the plate 90 is divided into two triangular fingers 94 which curve downwardly and rearwardly around the 30 platen, terminating slightly in the rear of the front edge of the paper apron 88 which is provided with the usual platen scale 95 (Figs. 2 and 5).

The paper guiding and controlling means 35 for the shorter or right-hand platen section comprises rear and front guide members designated generally by the respective reference numerals 96 and 97 and shown in detail in Figs. 8 and 9. The rear guide 40 member 96 may be made of two pieces of sheet metal soldered together, as shown. Said guide member 96 comprises a securing plate 98 which has an angularly disposed lip-like portion 99 provided with perforations 100. The lower end of the body portion 45 of the securing plate 98 is bifurcated to provide guide fingers 101 and soldered to said guide fingers are corresponding guide fingers 102 of a guide plate 103. The 50 guide plate 103 is provided with guide portions 104 which are formed from lateral extensions on the body of the guide plate 103, said lateral extensions being bent as indicated at 105 toward each other and over 55 the guide plate so as to provide guide slots 106. The rear ends 107 of the guide portion 104 are curved up away from the body of the plate 103 and corresponding curved portions 108 extend from the top of the 60 body portion 103 behind the ends 107. The pairs of curved ends 107 and 108 at each side provide a wide mouthed entrance to the guide slots 106 as will be plainly seen from Fig. 8. The rear guide member 96 is 65 secured to the under side of the plate-like

portion 70 on the platen frame by headed screws 109 (Fig. 4), which screws pass through the perforations 100 and are received in threaded openings in the portion 70. When fixed in position, as shown in 70 Figs. 3 and 4, the rear guide member 96 extends downwardly behind the right-hand platen section in place to guide the work sheet over said section, the guide fingers 102 pressing lightly against the surface of 75 the shorter platen section at the sides of the rivet heads or projections 49 and permitting said projections to pass between them as the platen section is rotated during the operation of the machine. The guide fingers 80 are sufficiently resilient to yield to let the work-sheet pass between them and the platen section. The guide member 97 is made preferably of a single piece of sheet metal which is cut out and bent back upon 85 itself to form guide fingers 110, a guide portion 111 and a securing portion 112 terminating in an angularly disposed lip 113. The lip is formed with perforations through which pass headed screws 114 (Fig. 3), 90 said screws being received in threaded openings in the under side of the front bar 6 of the platen frame and securing the front guide member 97 in place. Said guide member, it will be noted from an inspection of 95 Figs. 3 and 4, is adapted to receive the work sheet or paper as it leaves the rear guide member 96, the guide fingers 110 extending down from the front of the platen toward the ends of the rear guide fingers 100 102, pressing lightly against the platen and at their ends being curved away from the platen as indicated at 110^a (Fig. 3). The guide fingers 110 lie at the sides of the path taken by the hemispherical rivet heads 105 or projections 49 so that the latter may pass between said guide fingers as the platen section is given rotary movement, said guide fingers 110 yielding to permit the work sheet to pass between them and the platen 110 section.

The carriage truck 18 is provided near its middle with a rearwardly projecting guide arm 115 which controls a reciprocatory spool 116, said spool being mounted upon a rear 115 guide rod 117 fixed at the tops of standards 118 rising from the sides of the top plate 2 at its rear (Figs. 2 and 3). The left flange 119 of the spool 116 serves as a stop, which stop is adapted to coöperate with a line stop 120 120 adjustably mounted on a toothed stop bar 121 which stop bar is journaled on the standards 118. A margin stop 122 is adjustably mounted on the stop bar 121 at the right of the line stop 120, said margin stop 125 being provided with a stop lug 123 which is adapted to coöperate with a stop arm 124 secured to the carriage truck 18 by headed screws 125. It will be understood that the carriage is constantly urged leftward on its 130

track-ways 9 and 15 by a suitable carriage spring (not shown) and that the machine is provided with suitable escapement devices which coöperate in a known manner, when 5 the printing instrumentalities (not shown) are operated, to permit the carriage to be moved a letter space distance at a time by said carriage spring. The printing instrumentalities are of suitable construction and 10 preferably resemble those of the Remington machine, differing however in this respect that each type bar is in the present instance provided with one type instead of two, the character of work necessitating letters of one size only. It will also be understood that the flange 119 of spool 116 coöperates with the line stop 120 to limit the movement of the carriage in letter space direction and that the margin stop 122 15 operates with the carriage stop 124 to limit the movement of said carriage in return direction. The stop devices and the carriage feeding devices are of any suitable construction. The stop devices shown generally 20 resemble those of the Remington machine and the carriage feeding devices are preferably like the carriage feeding devices of the Remington machine. It is not deemed necessary to describe in detail these parts.

25 An indicator or pointer 126 of suitable construction is secured to the front guide rail 9 and said pointer coöperates with a scale plate 127 secured to arms 128 fixed to the front bar 6 of the platen frame. The 30 scale plate shown is a short one and is intended for use only with the short right-hand platen section which is wide enough for a line composed of only ten letters or so. This feature of the construction will be 35 more fully understood from subsequent explanations.

40 As has been stated the particular form of my invention herein shown is designed for use in writing car record tags or cards. For 45 convenience in preparing said cards they are supplied in the form of a continuous strip 129, a portion of which is shown in Fig. 15. The strip is perforated transversely at intervals, as indicated at 130, thereby dividing 50 it into sections 131 which may be readily separated or torn apart from one another after the strip has been fed through the machine and the tag sections or cards 131 have been written upon. Each tag section 55 or card is formed near one end with a round hole 132 by means of which the cards may be hung upon the hooks of the car record apparatus shown in the patent to Beecham hereinbefore referred to. To facilitate 60 the handling and manipulation of the continuous strip 129 by the typewriter operator, said strip is wound upon a core or center and is mounted upon a roll holder which will now be described. A V-shaped 65 bracket 133 (Figs. 1 and 2) is secured to the top plate of the machine by headed screws 134. The stem of the bracket supports a fixed upright post or spindle 135 which serves as a bearing for a hollow bearing sleeve 136 integral with and depending from 70 the base of a U-shaped bracket 137. The arms 138 of said U-shaped bracket are vertically disposed and receive between them a large roll holder or spool, between the flanges 139 whereof the strip 129 is arranged. The inner end of the strip 129 is preferably attached to a cylindrical wooden core 140 (Fig. 16) and the strip is wound thereon. The core 140 carrying the rolled up strip 129 is adapted to rotate upon the body portion of a shouldered and headed screw 141, which screw, as clearly shown in Fig. 16, passes through one of the bracket arms 138, thence through the contiguous flange 139, through the bore of the wooden core 140 and through the opposite flange 139, the threaded and reduced end 141^a of said screw being received in a threaded opening in the other bracket arm 138. The construction is such that the parts are connected together so that the core 140 and the rolled strip thereon may freely turn on the body portion of the screw 141 between the flanges 139. Rotary movement of the flanges 139 is prevented by screws 142 which pass 75 through one of the bracket arms 138 and screw into the contiguous flange 139. The free end of the rolled up strip 129 is passed outwardly over a pin 143 which is arranged between the flanges 139 at the front of the roll holder and near the periphery thereof.

80 Referring now to the operation of the paper feeding devices, the free end of the strip 129 after being passed forward over the pin 143, as shown in Fig. 1, is then in convenient position for being introduced into the wide or spreading mouth of the rear guide member 96, formed by the two sets of oppositely bent end portions or ears 107 and 108. The end of the strip 129 is passed down 85 through the slots 106 in the rear guide member, said guide being of sufficient width to permit the strip to pass freely therethrough and the construction being such that said strip is properly positioned widthwise of the 90 short platen section by said guide member. The strip is forced by the ends of the guide fingers 102 against the cover 41 of the short platen section and said platen section may be slightly turned to feed the strip and 95 bring one or another of the projections 49 into engagement with the first of the holes 132 in the strip. Thereafter as said shorter platen section is given rotary movement the projections 49 thereon engage one after another with successive openings 132 in the paper strip, protruding outwardly through said openings 132 and fitting snugly therein. The paper strip is thereby positively connected with the platen section and longitudi- 100

115

120

125

130

dinal displacement of the paper strip in respect of the platen section as said paper strip is fed through the machine is prevented while an exact and certain feeding movement of the strip is obtained. It will be understood, of course, that the projections 49 on the platen section are spaced apart a distance equal to the distance between the openings 132 in the paper strip, and, furthermore, that said projections are so related with the teeth of the line space wheel 44 that the line space detent 78 coöperating with said line space wheel will tend to maintain said paper strip in proper position for printing between the openings 132. After being fed forward from beneath the guide fingers on the rear guide member 96 the leading edge of the paper strip 129 will pass between the platen and the curved ends 110^a of the guide fingers 110 of the front guide member 97, said ends 110^a forming with the platen a sort of mouth or entrance for receiving the edge of the strip 129, said strip being pressed thereafter against the platen section by the guide fingers 110. The front and rear sets of guide fingers tend to maintain the strip 129 pressed against the under surface of the platen and in engagement with the projections 49 as shown clearly in Fig. 3. The relation between the platen section and the operative part of the strip 129 is best shown in Fig. 7. It is obvious that when the platen section is turned, the projections 49 at the lower part thereof engaging the sides of the openings 132 in the paper strip will force the latter to move around with the platen without possibility of relative displacement. By positively connecting the work sheet with the platen as described I provide a paper feeding means which is especially efficacious for thick paper, cards, stencil sheets and the like. It will be seen that I provide, in combination with a platen, a means operating automatically to positively connect the platen with the work sheet at varying points, so that a continuous work sheet may be employed and so that a work sheet may be held from displacement or displacement while in the machine and be positively fed forward as the platen section is rotated. Preferably when the end of the paper strip is introduced into the machine the conductor's report or other record (represented in Figs. 2 and 14 by the reference character 144) from which entries are to be made upon the sections 131 of the strip 129, is also entered in the machine in position to be fed around with the longer or left-hand section of the platen, the feed rollers 83 and the paper apron 88 coöperating with the platen to feed the record sheet 144 forwardly around with the longer platen section in the usual manner. After the leading edge of the record sheet 144 passes the edge

of the scale 95, on the paper apron, said record sheet will be guided by the fingers 94 of the indicating and guide plate 90 so that said record sheet will be fed around with the platen and will pass out of the machine in contact with the top edge of the line indicator 93, as will best be understood from a consideration of Figs. 5 and 14.

Referring now to the method of operating the devices generally, and more especially to the operation of the line space actuating mechanism so as to turn the platen sections to feed the strip 129 and the record sheet 144, it may be stated that in the present instance each line of the conductor's report or record sheet 144 furnishes data for writing two lines on each tag section 131, and the invention as shown is adapted therefore to line space the shorter platen section twice for each line space movement of the longer platen section. For the purposes of more clearly explaining the operation of the parts, it will be assumed that the tag strip has been fed into the machine in the manner hitherto described, that the first line of the first tag section to be written has been written and that said tag section has been thereafter line spaced once. Under these conditions the parts will be in the positions shown in Figs. 1, 2, 3, 4 and 14. In these figures the record sheet 144 is shown as it appears after it has been fed around with the longer section of the platen and so as to bring it to the position best illustrated in Fig. 14, wherein it will be noted the first line of writing on the record sheet is in register with the line indicator 93, said line of writing being represented by the cross marks indicated by the references *a* and *a'*, and the tag strip is in position for writing the second line of the first tag to be written from the data supplied by the latter part *a'* of the first line of the record sheet 144, it being assumed that the first line of the first tag section has already been written from the data obtained from the first part *a* of the first line on the record sheet 144 and that said tag section is now in position to have its second line written. As has been stated the tag strip 129 is wide enough for only ten letters or characters on the line. Consequently the scale plate 127 is provided with a scale having ten points only. The carriage, it will be noted, is in position such that the first point on the scale plate 127 registers with the indicator or pointer 126, and the margin stop 122 and the carriage stop 124 are in engagement so that the carriage cannot be moved any farther to the right. The second line of writing on the tag section now in printing position is next written in the ordinary manner by operating the printing instrumentalities, entries being taken from the latter part of the first line of the record sheet 144. As the

line is written the carriage will be moved one letter space at a time leftward across the top plate in a known manner and if ten characters be written on the tag section, 5 said carriage will be arrested by the engagement of the left flange 119 of the spool 116 with the line stop 120. During the movement of the carriage across the top plate the roll holder will be turned slightly 10 on its pivot 135 so that that portion of the tag strip 129 between the roll holder and the platen will not be bent or crumpled, nor will the free movement of the carriage be interfered with. It will, of course, be 15 understood that as the carriage is restored from left to right said roll holder will turn on its pivot 135 so that at the beginning of each line of writing the roll holder will be in the position shown in Fig. 2. The second 20 line of writing on the tag section having been completed, the line space lever 52 is operated by pulling the handle 53 forwardly, causing the pawl teeth 63 and 66 to coöperate with the teeth of their respective 25 line space wheels 44 and 34 to turn said line space wheels until the pawl 63 is arrested by the limiting stop 69 and effecting a forward feed of both platen sections. The line space wheels by this operation are 30 turned from the positions shown in Figs. 1 and 3 to the positions shown in Fig. 10. The amount of turning movement of the two line space wheels differs because of the difference in the distances their respective 35 pawl arms are pivoted from the fulcrum of the actuating lever 52, the construction being such that a differential line space movement of the two platen sections is effected by operating said lever 52. In Fig. 3 the 40 initial position of the teeth on the line space wheels with which the pawls 63 and 66 engage is indicated by the dotted radial line *b* and the positions of the said teeth at the completion of the line space movement are 45 respectively indicated in Fig. 10 by the dotted radial lines *c* and *d*. For purposes of comparison the initial position of the engaging teeth of said line space wheels is shown also in Fig. 10 and marked *b* as in 50 Fig. 3. From an inspection of Fig. 10 it will be noted that the line space wheel 34 has been moved through an angular distance measured by the angle inclosed between the radial lines *b*—*d*, said distance 55 being equal to the space between two of the teeth 39. Consequently the longer platen section, with which the line space wheel 34 is in fixed relation will also be turned through a distance equal to the space between two of the teeth 39. This movement 60 will bring the second line of writing on the record sheet 144 opposite the line indicator 93. By the same operation of the line space actuating lever, the line space wheel 65 64 has been moved a distance measured by 65 the angle inclosed between the radial lines *b*—*c*. It will be noted from an inspection of Fig. 10 that this angular distance is greater than the angular distance *b* *d* through which the line space wheel 34 has 70 been moved. The greater angular movement of the line space wheel 44 is sufficient to turn the smaller platen section, which is fixedly connected with said line space wheel, far enough to bring to the printing point 75 the first line on the tag section immediately following the tag section just completed. As soon as the actuating movement of the lever 52 has been completed said lever may be released and will be restored by its spring 80 55 into contacting engagement with the limiting stop-pin 56. During this restoring movement the pawl teeth 63 will be swung toward the front of the machine from the position shown in full lines in Fig. 10 to the 85 dotted line position of said pawl tooth shown in Fig. 11. During this movement of the pawl tooth 63 it will slide over one of the pointed ratchet teeth 45 and partially over the next preceding blunt or broad 90 faced ratchet tooth 46, coming to a state of rest at a point near the middle of the top face of said tooth 46 as shown by the dotted lines in Fig. 11. The pawl tooth 66 will move toward the front of the machine along 95 with the pawl tooth 63 and when said pawl tooth 63 comes to rest in the dotted line position the two pawl teeth 63 and 66 will be in substantially the same plane longitudinal 100 of the platen sections. During its movement toward the front of the machine the pawl tooth 66 will move forwardly out of that opening between the teeth 39 which is immediately in front of the dotted line *d* in Fig. 11, and when it comes to rest, the 105 point of said pawl tooth will lie above the next preceding opening between the teeth 39 on the ratchet wheel 34. Said pawl tooth will not enter said preceding opening 110 between the teeth 39, however, as will be understood from what follows. In its position of rest as shown by the dotted line position in Fig. 11 the point of the pawl tooth 63 rests on the periphery or crown of a broad tooth 46 of its associate ratchet wheel 115 so that the pawl 63 is somewhat elevated, being higher in the dotted line position of Fig. 11 than it was at the beginning of the line spacing operation as shown in Fig. 3. The pawl tooth 66 will be held up just above 120 the periphery of its associate ratchet wheel 34 by means of the connection or beat pin 67 which rises from the pawl arm 65 and lies over the pawl arm 62 so that when the latter is elevated, as shown by the dotted line 125 position of Fig. 11, the pawl arm 65 and its associate pawl tooth 66 will also be elevated. After the actuating lever 52 has been released and restored by its spring 55, carrying the pawl teeth to the positions just de- 130

scribed, the first line of the new tag section may be written, the data for said line being taken from, say the first part of the second line on the record sheet, which second line, 5 it will be recalled, is now in register with the line indicator 93. When the first line of the new or second tag has been filled in the carriage may be restored from left to right and the line space actuating lever 52 again 10 operated.

The first stage of the advance movements of the two pawl teeth 63 and 66 is shown in Fig. 11, the initial position of the pawl teeth 63 being indicated in dotted lines. From 15 a consideration of said figure it will be seen that the pawl tooth 63 first slides over the broad top face of the ratchet tooth 46 from the dotted line position to the full line position, in which latter position said pawl tooth 20 is shown as about to slide down into the opening just in the rear of the active ratchet tooth 46. During this first part of the movement of the pawl tooth 63 the pawl tooth 66 will move to the position indicated 25 in full lines in Fig. 11, and as it moves will be held out of engagement with its associate ratchet wheel by the connecting pin 67. As the actuation of the lever 52 is continued the pawl tooth 63 will move rearwardly and 30 downwardly into the opening or space between the ratchet tooth 46 and the ratchet tooth 45 and will, when fully engaged with said opening, be operative on the front or radial face of the ratchet tooth 45. As the 35 pawl tooth 63 starts to move downwardly into the opening or space between the teeth 46 and 45 the pawl tooth 66 will be permitted to move downwardly with it, but the parts are so proportioned that when the 40 pawl tooth 66 starts to move downwardly its rearward movement will have been sufficient to carry the point of said pawl tooth past the point of the ratchet tooth 39 from in front of which said pawl tooth 66 had 45 started. The result is that the pawl tooth 66 will move downwardly into that opening between the tooth 39 which is immediately in front of the dotted line *d* in Fig. 11. The completion of the actuating movement of 50 the lever 52 carries the pawls 63 and 66 from the positions shown in full lines in Fig. 11 to the positions shown in Fig. 12. As the pawl tooth 63 moves from the full line position in Fig. 11 to the position at 55 which it is arrested by the stop 69 as shown in Fig. 12, said pawl tooth, engaging the front of the ratchet tooth 45 as previously explained, will effect a rotary movement of the ratchet wheel 44, which rotary movement, 60 it will be understood, is measured by the difference between the angle inclosed between the radial lines *d*—*c'* in Fig. 12 and the angle *d*—*c* of Fig. 11. This movement corresponds to the distance from the top of 65 the engaging tooth 45 to the top of the next

preceding tooth and will serve to turn the smaller platen section through a corresponding distance so as to position the second tag section for writing the second line thereon. As the pawl tooth 63 moves from the position shown in Fig. 11 in full lines to that shown in Fig. 12, the pawl tooth 66 will move from the position shown in Fig. 11 to that shown in Fig. 12. Comparing these two figures it will be seen that the pawl 75 tooth 66 will simply slide down the inclined face of that ratchet tooth 39 which is in front of the dotted radial line *d*, and that when the pawl 63 is arrested by the stop 69 said pawl tooth 66 will have just fully engaged with the opening or space preceding the line *d*, but will not have affected the line space wheel 34. Consequently during the turning of the shorter platen section to move the first line of the second tag section away 80 from the printing point and to bring the second line of said tag section to the printing point, the longer platen section will remain motionless as will the record sheet 144. The operator may next refer to, say, 90 the last part of the second line on the record sheet, which line remains in register with the indicator 93, for the data for writing the second line on the second tag. It will be apparent that when the actuating lever 52 95 is released by the operator and restored by the spring 55, the line spacing wheels and their actuating devices will be in positions corresponding with those shown in Figs. 1 and 3. Consequently after the second line 100 on the tag section has been written the line spacing operations above outlined may be repeated as often as desired, so as to enable the third and subsequent tag sections to be written.

It will be apparent that at two successive movements or operations of the line space actuator 52 the line space wheel 34 and the longer platen section will have been turned only once while the line space wheel 44 and 110 the shorter platen section will have been turned twice. The distance, therefore, which the longer platen section has been turned corresponds to the angle between the lines *b*—*d*, and this is sufficient to move one 115 line of writing on the record sheet out of register with the line indicator 93 and to bring the next succeeding line into register with said indicator. The aggregate distance through which the shorter platen section will have been turned at two successive operations of the actuator 52 corresponds to the angular space between the radial lines *b*—*c'* in Fig. 12. As has been explained, 120 this aggregate turning movement of the 125 shorter platen section is made up of two successive movements, one of which is measured by the distance *b*—*c* in Figs. 10 and 11 and is considerably greater in extent than is the other movement which goes to com- 130

plete the aggregate movement measured by the lines $b-c'$. The reason for this difference in the movements will be understood from a consideration of Fig. 15, wherein 5 the lines of writing on several tag sections 131 are represented by cross marks and indicated by the reference characters e , f , and g respectively. The line e may be considered as the line written while the line space 10 wheels are in the positions illustrated in Figs. 1 and 3, this line being the second line on one of the tag sections. The line f will then be the line which is written when the line spacing wheels have been moved from 15 the positions shown in Fig. 3 to that shown in Fig. 10, said line f being the first line on the next succeeding tag section. The line g , which is the second line on said succeeding tag section will be written when the line 20 spacing wheels have been moved to the position shown in Fig. 12. It will be apparent from a consideration of Fig. 15 that it will be necessary, in order to get from the last line e on one tag section to the first line 25 f on the next succeeding tag section, to move the shorter platen section about three times as far as it is necessary to move or turn said platen section to get from the first to the second line on one of the tag sections. 30 It will also be seen that by providing the line spacing wheel 44 with two sets of teeth 45 and 46 of different dimensions and alternately arranged the mechanism is adapted so that the printing always comes 35 between the projections 49 and the latter are never brought into contact with the types.

I have described the longer platen section as serving in effect as a copy-holder which is automatically actuated intermittently to 40 bring successive lines to position to be copied upon the work sheet or tag strip 129. It will be obvious, however, that the longer platen section may be employed as a platen in the ordinary way and that a work sheet 45 may be fed around with said platen section in the same manner as the record sheet 144. It will furthermore be obvious that though I have shown and described the tag strip or work sheet 129 as being given alternately 50 varying extents of line space movement the parts may be constructed so that said tag strip need not be line spaced in this manner nor need the work or record sheet on the longer platen section be automatically line 55 spaced at every other movement of the work sheet 129 as described.

It is, I believe, novel to provide a divided or sectional platen with a single line space actuator which operates a plurality of 60 platen sections together at one time and which at another time operates only certain of said plurality of platen sections, while certain other of said plurality of platen sections remain inoperative, the change being 65 automatically effected and provision thus

being made for differential feeding of the work sheets coöperating with the platen sections. This principle I therefore desire to claim broadly and without limiting myself to a particular construction or to a particular operation. 70

While the long platen section, operated in the manner described to automatically position the record sheet, facilitates an accurate filling in of the tag strip or work sheet, 75 it should be understood that the operator may, if desired, copy the data from the record sheet in the ordinary manner and without introducing the record sheet into the machine. 80

I have shown my improvements, comprising the paper feeding and line spacing devices, as combined in a mechanism which facilitates the production of certain special work forms. It is obvious, however, that my novel devices instead of being employed in combination may be made use of separately or in different relations from those shown and explained. It is furthermore to be understood that from some aspects of my invention the shorter platen section may be regarded merely as a rotary device provided with means such as described for positively engaging and feeding the work sheet. 90 Various changes may be made in the construction and arrangement of parts without departing from the spirit and scope of my invention. 95

What I claim as new and desire to secure by Letters Patent, is:— 100

1. In a typewriting machine, the combination of a platen, line spacing and controlling devices for the platen, and a circularly arranged set of projections on the platen, said projections being spaced equally apart and being adapted to engage with perforations in a connected strip of tags, said devices controlling the platen so that the printing will take place intermediate said projections. 105

2. In a typewriting machine, the combination of a platen, line spacing and controlling devices therefor; a set of projections on the platen spaced equally apart and adapted to engage perforations in a strip of connected tags, said devices controlling the platen so that the printing will take place intermediate said projections; and paper guiding devices coöperative with the platen at opposite sides of said projections to guide the tag strip at both the introductory and delivery sides of the platen. 115

3. In a typewriting machine, the combination of a cylindrical rotary platen comprising a core and an external sheath, and a plurality of rivets connecting said core with said sheath, said rivets being arranged circumferentially of the platen and having heads projecting outwardly from the surface of the platen sheath and operative to 125 130

engage the work sheet and maintain a positive connection thereof with the platen.

4. In a typewriting machine, the combination of a cylindrical rotary platen comprising a core and an external sheath, and a plurality of rivets connecting said core with said sheath, said rivets being arranged circumferentially of the platen and their external heads being rounded and operative to engage perforations in the work sheet.

10 5. In a typewriting machine, the combination of a platen frame, a cylindrical platen journaled thereon, a plurality of radial projections arranged circumferentially of the platen and operative to engage perforations in the work sheet as the latter is fed through the machine, a slotted guide member comprising spring guide fingers and secured at the rear of the platen frame, said 15 guide fingers being arranged one at each side of the path of said radial projections, and spring guide fingers secured at the front of the platen frame and arranged one at each side of the path of said radial projections.

20 6. In a typewriting machine, the combination of a platen frame, a cylindrical platen journaled thereon and comprising a core and an external sheath, a plurality of 25 rivets connecting said core with said sheath, said rivets being arranged circumferentially of the platen and being provided with rounded external heads operative to engage the work sheet and maintain a positive connection 30 thereof with the platen, a slotted spring guide secured at the rear of the platen frame and co-operative with said work sheet, and a spring guide secured at the front of the platen frame and co-operative with the work 35 sheet.

40 7. In a typewriting machine, the combination of a platen frame, a cylindrical platen journaled thereon and comprising a core and an external sheath, a plurality of 45 rivets connecting said core with said sheath, said rivets being arranged circumferentially of the platen and being provided with rounded external heads operative to engage perforations in a continuous work sheet, a slotted 50 guide member secured at the rear of the platen frame and provided with a plurality of spring fingers, and a plurality of spring guide fingers secured at the front of the platen frame.

55 8. In a typewriting machine, the combination of a work holder mounted on the machine frame and carrying a work sheet wound into a roll and rotatable in said work holder, said work sheet being provided with 60 perforations at intervals in its length, a platen frame, a cylindrical platen journaled thereon, a plurality of radial projections arranged circumferentially of the platen and operative to engage the perforations in the 65 work sheet, spring guide fingers secured at

the rear of the platen frame and co-operative with the work sheet, and spring guide fingers secured at the front of the platen frame and co-operative with the work sheet.

9. In a typewriting machine, the combination of a work holder mounted on the machine frame and carrying a work sheet wound into a roll and rotatable in said work holder, said work sheet being provided with perforations at intervals in its length, a 70 platen frame, a cylindrical platen journaled thereon and comprising a core and an external sheath, and a plurality of rivets connecting said core with said sheath, said rivets being arranged circumferentially of the 75 platen and being provided with rounded external heads operative to engage the perforations in the work sheet.

80 10. In a typewriting machine, the combination of a work holder mounted on the machine frame and carrying a work sheet wound into a roll and rotatable in said work holder, said work sheet being provided with perforations at intervals in its length, a 85 platen frame, a cylindrical platen journaled 90 thereon and comprising a core and an external sheath, a plurality of rivets connecting said core with said sheath, said rivets being arranged circumferentially of the platen and being provided with rounded external heads operative to engage the perforations in the work sheet, a slotted guide member provided with spring guide fingers, said guide member being secured at the 95 rear of the platen frame and co-operating with said work sheet, and spring guide fingers secured at the front of the platen frame and co-operative with said work sheet.

100 11. In a typewriting machine, the combination of a roll holder pivotally mounted on the frame of the machine and carrying a continuous work strip, said strip being wound into a roll and provided at regular intervals with perforations, a platen frame, a cylindrical platen journaled on said platen 105 frame and comprising a core and an external rubber sheath, a plurality of rounded projections arranged circumferentially of the platen sheath and operative in turn to engage the perforations in the work strip 110 so as to maintain a continuous positive connection between the work strip and the platen, a slotted guide secured at the rear of the platen frame and provided with 115 spring fingers, and spring fingers secured at the front of the platen frame.

12. In a typewriting machine, the combination of a platen frame or carrier, a platen mounted thereon, and a single means operating to communicate alternately varying 125 extents of line space movement to the work sheet.

13. In a typewriting machine, the combination of a platen frame or carrier, a platen mounted thereon, and a single means oper- 130

- ating to communicate to said platen alternately varying extents of line space movements, the variation in the extent of line space movement being automatically effected. 5
14. In a typewriting machine, the combination of a platen frame, a cylindrical platen journaled thereon, and a single means for communicating to said platen alternately varying extents of rotary line space movements, the variation in the extent of line space movement being automatically effected. 10
15. In a typewriting machine, the combination of a platen frame, a cylindrical platen journaled thereon, a plurality of devices arranged circumferentially of the platen and operative in turn to engage the work sheet to connect it positively with the platen, and line space actuating means operative on said platen to turn it, said means being arranged relatively to said devices so that the printing instrumentalities when actuated will always coöperate with said platen between said devices. 20
16. In a typewriting machine, the combination of a platen frame, a cylindrical platen journaled thereon, a plurality of devices arranged circumferentially of the platen and operative in turn to engage the work sheet to connect it positively with the platen, a line space wheel operatively connected with said platen and provided with a plurality of sets of teeth of different sizes 30 alternately arranged, and line space actuating mechanism operative on the teeth of said line space wheel to turn said platen so that the printing instrumentalities when actuated will always coöperate with said platen between said devices. 35
17. In a typewriting machine, the combination of a platen frame, a cylindrical platen journaled thereon, a plurality of projections circumferentially arranged on said platen and operative to engage perforations in the work sheet, a line space wheel operatively connected with said platen and provided with a plurality of sets of teeth of different sizes alternately arranged, and line 45 space actuating mechanism operative on the teeth of said line space wheel to turn said platen so that the printing instrumentalities when actuated will always coöperate with said platen between said projections. 50
18. In a typewriting machine, the combination of a platen frame, a divided cylindrical platen journaled thereon and comprising a plurality of sections having coincident axes of rotation, one of said sections being provided with a plurality of projections circumferentially arranged and operative to engage perforations in the work sheet to connect it positively with said platen section, a line space wheel operatively connected with said last named platen section 65
- and provided with a plurality of sets of teeth of different sizes alternately arranged, a line space actuating lever pivoted to said platen frame, a pawl pivoted to said lever and operative on the sets of teeth of said line space wheel to turn said last named platen section so that said printing devices when actuated will always coöperate with said platen section between the projections thereon, a second line space ratchet wheel operatively connected with another of said platen sections, and a second pawl pivoted to said line space lever and operative on said second line space ratchet wheel, said line space lever being operative to actuate both 70 said pawls. 75
19. In a typewriting machine, the combination of a platen frame, a divided cylindrical platen journaled thereon and comprising a plurality of sections having coincident axes of rotation, one of said sections having a plurality of projections circumferentially arranged and operative to engage perforations in the paper, a line space wheel operatively connected with said last named platen section and provided with a plurality of sets of teeth of different sizes alternately arranged, a pawl operative on the teeth of said line space wheel, a second line space ratchet wheel operatively connected with another of said platen sections, a pawl operative on said second line space wheel, and a single lever operative to actuate both said pawls. 80
20. In a typewriting machine, the combination of a platen frame, a divided cylindrical platen journaled thereon and comprising a plurality of sections having coincident axes of rotation, one of said sections being provided with a plurality of devices arranged circumferentially and operative in turn to engage the work sheet, a line space wheel operatively connected with said last named platen section and provided with a plurality of sets of teeth of different sizes alternately arranged, a line space actuating pawl coöoperative with said sets of teeth, a second line space ratchet wheel operatively connected with another of said platen sections, a second pawl coöoperative with the second line space ratchet wheel, and a single member operative to actuate both said pawls. 90
21. In a typewriting machine, the combination of a platen frame, a divided cylindrical platen journaled thereon and comprising a plurality of sections having coincident axes of rotation, one of said sections being provided with a plurality of devices arranged circumferentially and operative in turn to engage the work sheet, line space actuating mechanism operative on the last mentioned platen section to turn it so that the printing instrumentalities when actuated will always coöperate with said platen between said devices, a line space ratchet 100
- 110
- 115
- 120
- 125
- 130

wheel operatively connected with another of said platen sections, a pawl coöperative with said line space ratchet wheel, and a single member operative to actuate said pawl and said line space actuating mechanism.

5 22. In a typewriting machine, the combination of a platen frame, a divided cylindrical platen journaled thereon and comprising a plurality of sections having coincident axes of rotation, a line space wheel 10 operatively connected with one of said sections, a pawl operative on said line space wheel, a second line space wheel operatively connected with another of said platen sections, a pawl operative on said second line space wheel, and a single actuator operative on both said pawls.

15 23. In a typewriting machine, the combination of a platen frame, a divided cylindrical platen journaled thereon and comprising a plurality of sections having coincident axes of rotation, a line space wheel operatively connected with one of said sections, a second line space wheel operatively connected with other of said sections, and pawls coöperating with said line space wheels, said pawls being operative by a single means.

20 24. In a typewriting machine, the combination of a divided cylindrical platen comprising a plurality of co-axial separate sections, a plurality of line spacing mechanisms one for each separate section, and a single means for operating said line spacing mechanisms, the sections being turned to provide for differential feeding of the work sheets under control of said single means.

25 25. In a typewriting machine, the combination of a platen frame, a platen axle journaled thereon, a platen section fixed to said axle, a second platen section rotatable on said axle, said platen sections being disconnected, mechanism for communicating rotary movement to each of said sections, and a single means for operating said mechanism.

30 26. In a typewriting machine, the combination of a platen frame, a platen axle journaled thereon, a platen section fixed to said platen axle, a second platen section rotatable on said platen axle, means for intermittently turning said first named platen section, means for intermittently turning said second named platen section, and a single actuator for operating both said turning means.

35 27. In a typewriting machine, the combination of a platen comprising two sections, and means operative to turn both of said sections at one time, said means including devices automatically effective to render said means operative at another time to turn one only of said platen sections while the other of said platen sections remains quiescent.

40 28. In a typewriting machine, the combination of a divided platen comprising a plurality of sections, and means automati-

cally operative alternately to turn said plurality of platen sections simultaneously and then to turn certain only of said plurality of platen sections while certain other of said sections remains unoperated.

45 29. In a typewriting machine, the combination of a divided platen comprising a plurality of sections, line space wheels one operatively connected with each of said platen sections, pawls coöperative with said line space wheels, a lever to which said pawls are pivoted, one of said pawls being operative at each actuation of said lever and another of said pawls being operative at alternate actuations of said lever.

50 30. In a typewriting machine, the combination of a divided platen comprising a plurality of sections, line space wheels one operatively connected with each of said platen sections, pawls coöperative with said line space wheels, a lever to which said pawls are pivoted, one of said pawls being operative whenever said line space lever is actuated and another of said pawls being operative at certain actuations only of said line space lever.

55 31. In a typewriting machine, the combination of a divided platen comprising a plurality of sections, line space wheels one operatively connected with each of said platen sections, and pawls coöperative with said line space wheels, certain of said pawls being controlled by certain other of said pawls.

60 32. In a typewriting machine, the combination of a divided platen comprising a plurality of sections, line space wheels one operatively connected with each of said platen sections, and pawls coöperative with said line space wheels, one of said pawls being controlled by another of said pawls so that the controlled pawl is at times inoperative.

65 33. In a typewriting machine, the combination of a divided platen comprising a plurality of sections, line space wheels, one operatively connected with each of said platen sections, pawls coöperative with said line space wheels, and a lever for actuating said pawls, one of said pawls being controlled by another of said pawls so that said controlled pawl is rendered inoperative at alternate actuations of said line space lever.

70 34. In a typewriting machine, the combination of a divided platen, line spacing means for one of the sections of the platen, and means for automatically giving a different extent of line spacing movement to another section of said platen when said line spacing means are actuated.

75 35. In a typewriting machine, the combination of a cylindrical platen, a line space wheel operatively connected therewith, a line space pawl therefor, a cylindrical copy

- holder co-axial with said platen, a line space wheel operatively connected therewith, a line space pawl therefor, a single actuator operative on said pawls to line space said platen and to rotate said copy holder to bring different lines of the copy into view, said actuator being effective to turn said platen and said copy holder to advance differentially the respective sheets thereon, and an indicator coöperating with said copy holder.
36. In a typewriting machine, the combination of a cylindrical platen, a line space wheel operatively connected therewith, a line space pawl therefor, a cylindrical copy holder co-axial with said platen, a line space wheel operatively connected therewith, a line space pawl therefor, and a single actuator operative on said pawls to line-space said platen and to rotate said copy holder to bring different lines of the copy into view, said actuator being effective to turn said platen and said copy holder to advance differentially the respective sheets thereon.
37. In a typewriting machine, the combination of a platen frame, a cylindrical platen, means including a hand lever for communicating rotary line space movements to said platen, and a cylindrical copy holder journaled on said platen frame co-axially with said platen and disconnected from said platen, said copy holder being automatically operative by said line space hand lever, said lever operating to turn said platen and said copy holder to advance the respective sheets 35 differentially.
38. In a typewriting machine, the combination of a platen frame, a cylindrical platen, means including a hand lever for communicating rotary line space movements 40 to said platen, and a cylindrical copy holder journaled on said platen frame and automatically operative by said line space hand lever at certain actuations only thereof.
39. In a typewriting machine, the combination of a platen, line space means therefor, and a copy holder mounted on the machine co-axially with said platen and disconnected from said platen, said copy holder being automatically operative by said line 50 space means, said means being operative to turn the platen and the copy holder so as to advance differentially the respective sheets thereon.
40. In a typewriting machine, the combination of a platen, line space means therefor, and a copy holder mounted on the machine and automatically operative by said line space means at certain actuations only of the latter.
- Signed at the borough of Manhattan, city of New York, in the county of New York, and State of New York, this 29th day of March, A. D. 1906. 55
